UNITED STATES PATENT OFFICE.

CHARLES W. BOOTH, OF CHICAGO, ILLINOIS.

CAR-DOOR STOP AND FASTENER.

1,180,002.

Specification of Letters Patent. Patented Apr. 18, 1916.

Application filed November 24, 1913. Serial No. 802,806.

To all whom it may concern:

Be it known that I, CHARLES W. BOOTH, a citizen of the United States, and resident of Chicago, in the county of Cook and State 5 of Illinois, have invented a new and useful Car-Door Stop and Fastener, of which the following is a specification.

This invention relates to combination door stops and fasteners for box cars.

10 The object of the invention is to provide a combination door stop and fastener for box cars which shall be reversible, that is which may be used in connection with a door opening either to the right or to the 15 left.

To this end a combination door stop and fastening member of my invention comprises the various features, combination of features and details of construction hereinafter 20 described and claimed.

In the accompanying drawings, in which my invention is fully illustrated, Figure 1 is a plan view of a combination door stop and fastening member of my invention, 25 shown as applied in use. Fig. 2 is a central, longitudinal sectional side view of my improved combination door stop and fastening member; and Fig. 3 is a sectional end view thereof on the line 3—3 of Fig. 1.

30 Referring now to the drawing A designates the body portion of a box car, B the car door and C the door stop, as a whole, said door stop comprising end section C¹ made of wood and an intermediate metal 35 section C², preferably made of cast-iron. As shown, the ends of the wood sections C¹ of the door stop are rigidly connected to the intermediate metal section C², the ends of said wood sections being preferably mortised 40 into the ends of said metal section C² and being secured thereto by means of bolts c, which, as shown, are the bolts whereby the adjacent ends of the wood and metal sections of door stop are secured to the body 45 portion of the car.

In order to reduce the weight of the metal section C² of the door stop said door stop is preferably recessed on its rear side, as shown at c¹, and for reasons presently apparent, a slotted opening c² is formed 50 through the metal section C² of the door stop, said opening c² being located centrally of said door stop, and being substantially symmetrical on both sides of the transverse 55 center thereof. Formed in the outer side of said metal section C² at the ends of said

slot c² are recesses c³ which are adapted to receive the heads of bolts c⁴, which with the bolts c secure the metal section C² of the door stop to the body portion A of the car. 60 Said recesses c³ are only slightly larger than the heads of the bolts c⁴ so that the sides of said recess will closely embrace the heads of said bolts, thus securing said bolts against turning and effectually preventing the removal of the metal sections C² of said door stop from the outside of the car. The metal section C² of said door stop, is reinforced and strengthened by means of a bracket D rigidly connected thereto and preferably 65 formed integral therewith, the outer end of said bracket being provided with a bolt hole to provide for bolting it to the side of the car body.

70 Preferably, also the metal stop section C² comprises a lip E, preferably formed integral therewith, which projects inwardly from said door stop so as to engage the edge of the door as said door is closed and to 75 guide and hold said door firmly against the side of the car, when said door is in closed position. As shown, also, the metal stop section C² is utilized as the base or support of one member of the door fastener, said stop section C², as it relates to fastening 80 means for the door, being so constructed and arranged that it may be used with either end of said metal stop section C² uppermost, thereby rendering said stop reversible and adapting it for use with doors which open away from said stop either to the right or to the left. As shown, also, the structure of said metal stop section C², as it relates to the fastening means, is of the type 85 in which the locking bolt is confined and is freely movable endwise in suitable guide bearings formed in lugs which project outwardly from the front side of said metal stop section C², and is adapted to be inserted into its bearings in said lugs from the back 90 side of said metal stop section through a suitable hole or opening formed therein.

95 As shown, the locking pin 1 is mounted so as to be freely movable endwise in guide bearings formed in a center lug 2 and in the lower of two similar hasp lugs 3 and 4, which are symmetrically located on opposite sides of the center lug 2 at a distance therefrom and in line therewith.

100 As shown, the bearings for the locking pin 1 in the lugs 3 and 4 consist of holes 5 formed therein to which the body portion

of the locking pin 1 is fitted so as to be freely movable therein, and the bearing for the said locking pin in the lug 2 is formed by the outer section of a slot 6 in said lug, said slot 6 forming a continuation of the slotted opening c^2 in the body portion of said metal stop section C² and, with said slot c^2 provides a continuous opening extending from the back side of said metal stop section to the outer end of said slot 6.

The bearings for the locking pin 1 in the center lug 2 is formed by the outer section of the slot 6, said locking pin when inserted into its bearing in said center lug being confined therein by projections 7 formed on opposite sides of the slot 6 and which extend inwardly toward each other, and the adjacent ends thereof being separated from each other by a space which is smaller than the normal thickness of said bolt 1. To provide for inserting the locking pin 1 through the opening c^2 and the slot 6 past the projections 7 into its bearing in the center lug 2, notches 8 are formed in opposite sides of the locking pin 1 which are somewhat wider than the width of said projections and are slightly deeper than the height thereof, so that when said notches 8 are brought into register with the said projections 7, said locking pin will be narrower than the space between the ends of said projections 7, thus permitting said locking pin to be inserted past the projections 7 into its bearing in the outer end of the slot 6.

Disengagement of the locking pin 1 from its bearings in the center lug 2 and in either of the hasp lugs 3 or 4 is prevented by a head or hook 9 formed on the upper end of the locking pin, contact of which with the lug 2 limits the downward movement of said pin, and the hasp lugs 3 and 4, which are of such size and are so positioned relatively to the center lug 2 that the lug 3 or 4, between which and said lug 2 the headed end of said bolt is positioned, will form a stop which will limit the upward movement of said locking pin and will prevent its withdrawal from its bearing in said lug 2.

The opening c^2 is made of such length that the distance from the end of said opening to a line extending through the centers of the projections 7 will be slightly greater than the distance from the extreme upper end of the locking pin 1 to a line passing through the centers of the recesses 8 in said locking pin. Also, the locking pin 1 is designed and adapted to be inserted into its bearings from the rear side of the stop section C² before said stop section is secured in position in the car body at the side of the door opening. With the described construction, when the locking bolt 1 and the securing bolts c^4 are inserted into position in the metal stop section C², the heads of the

bolts c^4 will close the ends of the slotted opening c^2 and will thus prevent the locking bolt 1 from passing into said opening c^2 after said metal stop section has been secured to the car, which would render it impossible to operate the same. 76

As shown, the locking pin 1 is longer than the opening c^2 and to insert said pin through said opening c^2 into its guide bearings it is necessary to first insert the small end of said locking pin through said opening 2 a sufficient distance to bring the recesses 8 in said pin into register with the projections 7 on the sides of the slot 6, which will permit said pin to pass said projections into engagement with its guide bearing in the lug 2 and the headed end of said locking pin to clear the end of the opening c^2 , all as heretofore described. 75

The described manner of inserting the locking pin 1 through the slotted opening c^2 past the portions 7 on the side of the slot 6 and into engagement with its guide bearing in the outer end of the slot 6 is illustrated in Fig. 2 of the drawing, which shows the pin in dotted lines in two positions, designated, respectively, 1¹ and 1², 1¹ showing the position of the locking pin at the beginning of the operation of inserting said locking pin through the opening c^2 , 95 and 1² showing the position of the locking pin when it has been inserted through the opening c^2 a sufficient distance to bring the recesses 8 into register with the projection 7. The locking pin 1 is shown in full lines in 100 engagement with its guide bearings.

The hasp lugs 3 and 4 correspond to the staples of an ordinary hasp and staple lock, and with my improved combination door stop and fastener, the fastener hasp is secured to the car door A' substantially in line with the lower hasp lug 3, in such position that it may be readily engaged therewith. 105

In locking the door, the locking bolt 1 is lifted so that its lower end will be above 110 the hasp lug 3, the hasp 10 is then placed over the lug 3 and the locking bolt 1 is lowered or dropped into engagement with the guide bearing 5 in said lug.

To provide for sealing the lock or fastening means, a slotted opening 11 is formed in the locking pin 1 in such position that it will be below one or the other of the lugs in which said locking pin is confined and in such proximity thereto that when said locking pin is raised, the sealing means will contact with the adjacent lug before said locking pin is raised a sufficient distance to disengage it from its bearing in the hasp lug 3 and to permit the door hasp 10 from being moved out of engagement with said lug. 115

In the preferable construction shown, the sealing means for my improved combination door stop and fastener comprises similar 120

lugs 12 and 13 which are arranged in pairs on opposite sides of the center lug 2 and at opposite sides of the opening c^2 , said lugs 12 and 13 being preferably formed integral with said lug 2 and extending lengthwise of the slotted opening c^2 . Formed through said lugs 12 and 13 are openings 14 and 15, the relative positions of said openings being such that when said metal stop section is secured to the car body, the lower of said openings will register with the opening 11 in the locking pin 1 when said locking pin is in full locking position, as shown in full lines in Fig. 1 in which the openings 14 are in register with the opening 11 in said locking pin 1.

The construction shown is adapted for use with the familiar form of car door seal consisting of a thin metal band adapted to be inserted through the registered openings 11 and 14 and the ends thereof connected by means of a lead or other soft metal seal. In the drawing, in which I have shown a seal of this character, 16 designates the metal band inserted through the openings 11 and 14, and 17 the seal which connects the ends of said band.

Obviously, by substituting for the metal stop section or body portion C^2 , a flat web or plate, a reversible door fastening member would be provided adapted for use with any usual form of door stop.

I claim:

1. A locking member for car door fasteners, comprising a base provided with an opening which extends through the same from back to front, a lug on the front side of said base which extends across the opening therein and is provided with a slot which forms an extension of the opening through said base, a locking bolt, a projection on a side of the slot in said lug which defines a bearing for said locking bolt at the outer end of said slot, a hasp lug on said base provided with a bearing for the locking bolt, said locking bolt being provided with a recess to permit its insertion from the back of said base through the opening therein, past the projection on the side of the slot in said slotted lug into engagement with its bearing in said lug, withdrawal of said locking bolt from its bearing in said slotted lug in one direction being prevented by contact of rigid parts of said bolt and base, substantially as described.
55. 2. A locking member for car door fasteners, comprising a base provided with an opening which extends through the same from back to front, a lug on the front side

of said base which extends across the opening therein and is provided with a slot 60 which forms an extension of the opening through said base, a locking bolt, a projection on a side of the slot in said lug which defines a bearing for said locking bolt at the outer end of said slot, a hasp lug on said base 65 provided with a bearing for the locking bolt, said locking bolt being provided with a recess to permit its insertion from the back of said base through the opening therein, past the projection on the side of the slot in said 70 slotted lug into engagement with its bearing in said lug, withdrawal of said locking bolt from its bearing in said slotted lug in one direction being prevented by contact of the head of said bolt with said slotted lug 75 and in the opposite direction by contact of the headed end of said bolt with a rigid part of said base, substantially as described.

3. A combination door stop and fastening member for box cars, comprising a body 80 portion provided with an opening extending through the same from back to front, a lug on the front side of said body portion which extends across the opening therein and is provided with a slot which forms an extension of the opening through said body portion, 85 a locking bolt, projections on the sides of the slot in said lug, which define a bearing for said locking bolt at the outer end of said slot, hasp lugs at opposite sides of said 90 slotted lug provided with bearings for the locking bolt, said locking bolt being provided with recesses to permit its insertion from the back side of said body portion through the opening therein, past the projections on the sides of the slot in said intermediate lug into engagement with its bearing in said lug, a head on said locking bolt, withdrawal of said locking bolt from its bearing in said slotted lug in one direction 95 being prevented by contact of the head of said bolt with said slotted lug and in the opposite direction by contact of the headed end of said bolt with the hasp lug between which and said slotted lug the headed end 100 of said bolt is positioned, substantially as described.

In testimony that I claim the foregoing as my invention, I affix my signature in the presence of two subscribing witnesses, this 110 18th day of November, 1913.

CHARLES W. BOOTH.
